CONTROL DEVICE

Clarence Wantz, Milwaukee, Wis., assignor to
Milwaukee Gas Specialty Company, Milwaukee,
Wis., a corporation of Wisconsin

Original application November 10, 1938, Serial
No. 239,790, now Patent No. 2,307,870, dated
January 12, 1943. Divided and this applica-
tion February 23, 1942, Serial No. 432,053

5 Claims. (Cl. 137—144)

This invention relates to a control device for heating and other apparatus, and has particular relation to an improved thermoelectric safety shutoff device.

The present application is a division of my co-pending application Serial No. 239,790, filed November 10, 1938, and now Patent No. 2,307,870, granted January 12, 1943.

One of the main objects of the present invention is to provide an improved form of safety reset means having means for shutting off the supply of fluid through the conduit, and particularly the flow of fuel to the main burner during the operation of resetting the armature to attracted position and the safety shutoff valve to open position, and, further, having a packless reset stem provided with a valve member which cooperates with the valve body to prevent leakage from the valve body along the reset stem when the reset stem is in its outer position.

Further objects and advantages of the invention will be apparent from the following detailed description, taken in connection with the accompanying drawing in which the single figure is an axial section through a thermoelectric safety shutoff device embodying the present invention, showing more or less diagrammatically the thermocouple or thermoelectric generator connected in circuit with the electromagnet, a main burner, and a pilot burner for lighting the main burner and for heating the thermocouple.

Referring to the drawing, the burner 10 is any suitable or preferred main burner—by way of example, for an oven, or for a room heater or a water heater, or it may be one of the main top burners of a gas range, or any other main burner.

A pipe 11 supplies gaseous or any other suitable fuel to the burner 10, and disposed in juxtaposition to the burner 10 is a pilot burner 12 which maintains a pilot light 13 for igniting the main burner. The pilot burner 12 is supplied with fuel by a tube 14 connected, for example, at 15, to the interior of the valve body 20, by way of example through one or more ports and an annular groove in the valve seat member 65 within the length of said member. The tube 14 may, of course, be connected to the fuel supply pipe 11 anterior of the valve body 20 within the scope of the present invention.

The thermoelectric control device, designated in its entirety at 18, comprises a valve body 20 having an inlet 21 and an outlet 22 for connection into the fuel supply pipe 11.

The lead-connection cap and magnet and armature housing assembly is mounted upon the top of

the valve body 20 as the same is viewed in the drawing, and, when in place, closes the upper end of the bore 23 therein. The lead connection cap 24, which is preferably formed of "Bakelite" or any other suitable or preferred insulating material, may be of the external form more fully disclosed in the parent application, or of any other suitable or preferred form. It has at its inner end an integral cylindrical extension 25 which fits into a counterbore 26 at the outer end of the bore 23, and the cap 24 is fastened in place upon the outer end of the valve body 20, for example by cap screws (not shown), and preferably with a sealing gasket or washer 28 between the cap and the valve body.

The magnet housing 30 is in the form of an outwardly opening cup-shaped metal shell mounted on the cap 24, for example by secure pressed fit engagement of its outer open end in the cap 24 at 32. The housing or shell 30 is reduced at its inner end at 33, and the armature housing 34, which is also in the form of an outwardly opening cup-shaped metal shell, is mounted on the shell 30, for example, by secure pressed fit engagement of its open outer end telescopically over the reduced inner end 33 of the shell 30. The inner end of the shell 34 is preferably reduced as shown.

The electromagnet comprises a generally U-shaped magnet frame 36 positioned within the shell 30 with its legs extending through openings in the inner end of this shell and presenting pole ends within the armature housing 34. The magnet frame 36 has a threaded stud 37 integral therewith or welded or otherwise rigidly joined thereto. This stud 37 extends into an opening or recess 38 in the top of the cap 24, and has threaded engagement with a nut member 39 for clamping the magnet frame rigidly and, at the same time, removably in place. The nut member 39 has a kerf 40 for engagement by a screw driver or other suitable tool, and a spring washer may be provided between the nut member 39 and the bottom of the recess 38 as indicated at 41.

Fixed rigidly in the cap 24, as, for example, by molding the insulating material of the cap thereto and extending endwise from the cap are a pair of spaced metallic terminal members 42 and 43 having aligned openings 44 and split outwardly of these openings as shown at 45. The coil 46 of the electromagnet surrounds the legs of the magnet frame 36, and the leads or ends of this coil extend out through the terminal members 42 and 43 and have their bared ends connected to the terminal members 42 and 43 at 47 and 48,

respectively, in a manner to have good conducting contact therewith. The connections at 47 and 48 are shown disposed outside of the cap 24 and laterally of the openings for receiving the terminal means on the thermocouple lead conductors. The coil 46 is preferably covered with insulation between its bared ends at 49. Suitable insulation may be interposed between the turns of the coil 46 and the legs of the magnet frame 36, and between the inner end of the shell 30 and the adjacent end of the coil 46 as shown, by way of example, at 51 and 52, respectively.

The armature 55 is disposed in the armature housing 34 and is adapted to be held in attracted position against the pole ends of the magnet frame 36 upon energization of the electromagnet. The armature 55 is of disc-like form and is secured to the outer end of a reciprocating valve stem 57. The attachment of the armature to the valve stem 57 at 58 is preferably sufficiently loose, as indicated at 59, to permit self-accommodation of the armature to the pole ends of the magnet frame by a generally universal movement of the armature upon the outer end of the valve stem. The stem 57 is disposed generally concentrically with respect to the armature housing 34 and extends inwardly for reciprocating movement through an opening 60 in the inner end of the housing 34.

The valve member 62 is fixed by a pin 63 upon the inner end of the valve stem 57 preferably for some relative movement thereon so as to have self-accommodating seating engagement with the cooperating valve seat 64 at the outer end of the valve seat member 65. Packing 68, of felt or other suitable or preferred material, is interposed between the bottom of the armature housing 34 and a metal valve spring seating disc 69. The valve spring 70 is in the form of a coiled compression spring interposed between the valve member 62 and the spring seating disc 69, and, if desired, centered at opposite ends about integral hub-like portions on the valve member 62 and the valve seating disc 69. The spring 70 resiliently moves the armature 55 to retracted position and the valve member 62 into seating engagement with the valve seat 64 to shut off the flow of fuel to the outlet 22 and thereby to the main burner when the electromagnet is de-energized.

The disc 69 seats inwardly upon a shoulder 72 in the bore 23, and the action of the spring 70 tends to compress the packing 68 and maintain same in sealing engagement with the bore 23 and with the valve stem 57 to seal the interior of the armature housing 34 from the gaseous or other fuel which passes through the valve body, and to seal the valve body against the escape of fuel out around the cap and magnet and armature housing assembly. The device is further sealed against the escape of fuel by the gasket or washer 28.

From the foregoing description it will now be apparent that the armature housing 34 is detachable from the magnet housing 30 to permit access to the armature 55 and to the pole ends of the magnet frame 36. The magnet housing 30 may also be adapted for detachment from the lead connection cap 24 to permit access to the magnet frame 36 and magnet coil 46.

The thermocouple 75 selected for illustration is of the type disclosed and claimed in Oscar J. Leins Patent No. 2,126,564, granted August 9, 1938. It comprises an outer tubular metallic thermocouple member 76 and an inner metallic ther-

mocouple member 77 disposed within the outer thermocouple member and joined at one end to the end of the outer thermocouple member to form the thermojunction 78 which is placed in position 5 to be heated by the pilot light 13. An inner lead conductor 79 is joined to the inner thermocouple member to form an internal thermojunction 80, and an outer tubular lead conductor 81 is connected to the outer thermocouple member through 10 a sleeve 81' to form a third thermojunction 82. The outer lead conductor 81 encloses the inner lead conductor and, with the outer thermocouple member, constitutes an enclosure about the inner thermocouple member and the inner lead conductor 15 and the inner thermocouple junction 80. The inner lead conductor 79 is insulated from the outer lead conductor by a wrapping of insulation on the inner lead conductor as indicated at 84. The inner and outer lead conductors 79 and 81 20 are preferably of a character which will permit bending, as desired, to permit disposing the thermocouple in any desired position. At the same time the lead connection is preferably of a character to support the thermocouple in any desired position, although supporting brackets or other means may be employed for supporting the thermocouple and lead connection. At the opposite end the inner lead conductor 79 extends from the outer lead conductor 81 and has a metallic terminal sleeve 86 fixed thereon in good 25 conductive contact therewith and spaced from the end of the outer lead conductor 81. An insulating sleeve 87 is interposed between the terminal sleeve 86 and the adjacent end of the outer lead conductor 81.

A quick detachable connection is thus provided between the thermocouple leads and the terminals 42 and 43 for the electromagnet coil 46. The thermocouple is connected to the terminals 42 and 40 43 by slipping the terminal end of the thermocouple lead means through the opening 44 in one terminal member 43 and into the opening 44 in the other terminal member, with the terminal sleeve 86 in the opening 44 in one terminal member 42 and the end of the tubular thermocouple lead 81 in the opening 44 in the other terminal member 43. The screws 90 are then tightened to 45 clamp the split portions 45 of the terminal members 42 and 43 into good conductive contact and gripping engagement with the terminal sleeve 86 and tubular lead 81, respectively. The thermocouple is disconnected from the device by loosening the screws 90 and withdrawing the terminal end of the thermocouple leads from the terminal members 42 and 43.

The quick detachable connection permits the thermocouple with its leads to be detached from the control device in shipment. At the same time the thermocouple may be connected to the control device expeditiously, and when connected good conductive contact is assured. This is important where the electromotive force is a relatively weak thermoelectromotive force such as that produced by the heat of the pilot light 13 on the thermojunction 78 of the thermocouple.

The heat of the pilot light 13 upon the thermocouple is sufficient to hold the armature 55 in attracted position and the valve member 62 in open position, as shown, when the armature is engaged with the pole ends of the magnet frame, but this thermoelectric current is not capable of moving the armature to attracted position and the valve member 62 to open position. In order, therefore, to provide for opening the valve member 62 and for setting the armature to attracted

position upon the initial operation of the device and to reset the device after the same closes to shut off the fuel supply when the pilot light is extinguished, reset means is provided. This reset means comprises a reset stem 95 coaxial with the valve 62 and extending through the lower end of the valve housing 20. The stem 95 is provided at its outer end with a reset stem knob or button 96.

Fixed upon the stem 95 for reciprocatory movement therewith is a reset member 97 which has abutting engagement at 98 with a reset spring cup 99. A fuel flow interrupter spring 100 is interposed between the spring cup 99 and a flow interrupter disc valve 102, a retainer being provided at 103 for limiting inward movement of the disc valve 102 relative to the reset stem 95. The disc valve 102 is adapted to seat upon the valve seat 104 at the adjacent end of the valve seat member 65 to shut off or interrupt the flow of fuel to the outlet 22 and, thereby, to the main burner during the resetting operation and until the valve member 62 is held in open position by the thermoelectric current and the reset stem 95 is released.

The valve seat member 65 is in the form of a sleeve threaded into the valve body 20 at 105, and a coiled spring 106 is interposed between the shoulder 107 on the valve seat member 65 and the spring cup 99. The spring cup 99 is provided with a vent opening 108, and the reset member 98 has a conical valve part 109 which seats upon a shoulder 110 in the valve body and seals the opening 111 through which the stem 95 extends when the parts are positioned as shown.

The operation of the device is as follows:

When the pilot light 13 is burning the heat thereof upon the thermojunction 78 produces a thermoelectric current in the coil 46. The magnet frame 36 and armature 55 are preferably formed of an alloy of relatively low magnetic reluctance and, as a result, the relatively weak electromotive force produces a magnetic field of sufficient strength so that when the armature 55 is placed in contact with the pole ends of the magnet frame by pushing the reset button 96, the magnetic attraction holds the armature in attracted position as long as the pilot flame is burning.

If the pilot flame is extinguished, the holding action of the electromagnet ceases to be sufficient to hold the armature 55 in attracted position and the valve 62 in open position, and the spring 70 moves the armature to retracted position and the valve member to closed position. Where the device is installed vertically as shown, the spring is aided by gravity in closing the valve, but the spring is preferably of sufficient tension to close the valve without the aid of gravity, so that the device may be installed in any desired position. The spring 70 assures detachment of the armature 55 from the electromagnet upon deenergization of the electromagnet and notwithstanding any residual magnetization therein. The closing of the valve 62 shuts off the supply of fuel to the main burner.

When it is desired to reset the device, the reset button 96 is engaged with the hand and pressed inwardly. The accompanying inward movement of the stem 95 and reset member 97 moves the reset spring cup 99 inwardly against the tension of the springs 100 and 106. The reset member 97 forces the flow interrupter valve disc 102 inwardly through the spring 100 until the disc 102 seats upon the valve seat 104 and

interrupts or shuts off the flow of fuel through the outlet 22, and thereby to the main burner. Continued inward movement of the reset stem 95 brings the inner end of this stem into contact with the valve member 62 and moves this valve member and the valve stem 57 and armature 55 outwardly as a unit until the armature 55 comes into contact with the pole ends of the magnet frame 36 or is brought into attracted position and the valve member 62 is positioned in open position as shown in the drawing.

In resetting the device the flow interrupter valve disc 102 shuts off the outlet 22 against the passage of fuel therethrough while the valve 62 is in open position during the resetting operation, and, at the same time, fuel is free to pass through the pilot burner connection 15 to the pilot burner upon opening the valve member 62 in resetting the device. As the valve 62 is opened in the resetting operation, fuel passes out through the pilot port connection 15 to the pilot burner so that the pilot burner may be ignited to set up the thermoelectric current for energizing the electromagnet to hold the armature 55 in attracted position and the valve 62 open.

If the pilot burner 12 is lighted and sets up a thermoelectric current to hold the armature in attracted position, the valve 62 will remain open, and when the reset button 96 is released the springs 100 and 106, and particularly the reset spring 106, will return the reset button to its outwardly projected position as shown in the drawing. As the reset stem is projected to its illustrated position, the retainer 103 engages the valve disc member 102 and returns same to open position against the tension of the spring 100, whereupon the desired supply of fuel is set up to the burner 10 for ignition by the pilot light 13.

If, on the other hand, the pilot burner is not lighted to produce the thermoelectric current for holding the valve 62 open, this valve will move to closed position upon release of the button 96. In this manner the device prevents the passage of fuel through the outlet 22 to the main burner until the pilot burner is lighted and a thermoelectric current set up to hold the armature in attracted position.

I do not intend to be limited to the precise details shown or described.

I claim:

1. In a device of the character described, a valve body having an inlet and an outlet, a safety shutoff valve element having an open position and a closed position for establishing and shutting off communication between said inlet and outlet, an armature connected to said valve element, an electromagnet cooperable with said armature effective when energized to hold said armature in attracted position and said valve element in open position but ineffective to move said armature to attracted position and said valve element to open position, a reset stem movable inwardly through said valve body for resetting said armature to attracted position and said valve element to open position, a second valve element positioned on said reset stem having a closed position for shutting off communication between said inlet and outlet during the resetting operation and an open position, said reset stem being slidable through said second valve element, reset spring abutment means on said reset stem comprising a third valve element fixed on said reset stem, a reset spring within said body interposed between said abutment means and an abutment on said valve body for

returning said reset stem to its outer position upon completion of the resetting operation, retainer means on said reset stem, and a second spring within said body interposed between said abutment means and said second valve element so as normally to hold said second valve element against the retainer, the arrangement being such as to permit continued movement of said reset stem after seating of said second valve element during resetting operations and unseating thereof by return of said reset stem to its outer position, said third valve element cooperating with said valve body for forming a fluid tight closure about said reset stem in the outer position of the latter.

2. In a device of the character described, in combination, a safety shut-off device including a valve body, a passage therethrough adapted to be connected at one end to an inlet conduit and at its other end to an outlet conduit, said passage having a pair of coaxial spaced valve seats, a valve element coacting with one of said seats having an open position permitting the supply of fluid through said passage and a closed position shutting off the supply of fluid through said passage, an armature, an electromagnet cooperable with said armature, said electromagnet being effective when energized to hold said armature in attracted position and said valve element in open position but ineffective to move said armature to attracted position and said valve element to open position, a reset stem movable inwardly for resetting said armature to attracted position and said valve element to open position, a second valve element slidably mounted on said reset stem and arranged to cooperate with the other valve seat to shut off flow of fluid through the passage during a resetting operation, a reset spring abutment member on said reset stem, a reset spring interposed between said abutment member and an abutment on the valve body for returning the reset stem to its outer position upon completion of the resetting operation, retainer means on said reset stem, and a second spring interposed between said abutment member and said second valve element so as normally to hold said second valve element against the retainer, said second spring being disposed within the length of said first spring, the arrangement being such as to permit continued movement of said reset stem after seating of said second valve element during resetting operations and unseating thereof by movement of said reset stem to its outer position.

3. In a device of the character described, in combination, a safety shut-off device including a valve body, a passage therethrough adapted to be connected at one end to an inlet conduit and at its other end to an outlet conduit, said passage having a pair of coaxial spaced valve seats, a valve element coacting with one of said seats having an open position permitting the supply of fluid through said passage and a closed position shutting off the supply of fluid through said passage, an armature, an electromagnet cooperable with said armature, said electromagnet being effective when energized to hold said armature in attracted position and said valve element in open position but ineffective to move said armature to attracted position and said valve element to open position, a reset stem movable inwardly for resetting said armature to attracted position and said valve element to open position, a second valve element slidably mounted on said

reset stem and arranged to cooperate with the other valve seat to shut off flow of fluid through the passage during a resetting operation, a reset spring abutment member on said reset stem, a reset spring interposed between said abutment member and an abutment on the valve body for returning the reset stem to its outer position upon completion of the resetting operation, retainer means on said reset stem, a second spring interposed between said abutment member and said second valve element so as normally to hold said second valve element against the retainer, the arrangement being such as to permit continued movement of said reset stem after seating of said second valve element during resetting operations and unseating thereof by movement of said reset stem to its outer position, and a third valve member fixed on said stem and cooperable with the valve body to prevent leakage from the valve body along the reset stem in the outer position of said stem.

4. In a device of the character described, in combination, a safety shut-off device including a valve body, a passage therethrough adapted to be connected at one end to an inlet conduit and at its other end to an outlet conduit, said passage having a pair of coaxial spaced valve seats, a valve element coacting with one of said seats having an open position permitting the supply of fluid through said passage and a closed position shutting off the supply of fluid through said passage, an armature, an electromagnet cooperable with said armature, said electromagnet being effective when energized to hold said armature in attracted position and said valve element in open position but ineffective to move said armature to attracted position and said valve element to open position, a reset stem movable inwardly for resetting said armature to attracted position and said valve element to open position, a second valve element slidably mounted on said reset stem and arranged to cooperate with the other valve seat to shut off flow of fluid through the passage during a resetting operation, a reset spring abutment member on said reset stem, a reset member fixed on said stem providing an abutment for said abutment member, a coiled reset spring interposed between said abutment member and an abutment on the valve body for returning the reset stem to its outer position upon completion of the resetting operation, retainer means on said reset stem, and a second coiled spring interposed between said abutment member and said second valve element so as normally to hold said second valve element against the retainer, the arrangement being such as to permit continued movement of said reset stem after seating of said second valve element during resetting operations and unseating thereof by movement of said reset stem to its outer position, said second spring being arranged within the convolutions of said first spring with its length confined within the length of said first spring.

5. In a device of the character described, in combination, a safety shut-off device including a valve body, a passage therethrough adapted to be connected at one end to an inlet conduit and at its other end to an outlet conduit, said passage having a pair of coaxial spaced valve seats, a valve element coacting with one of said seats having an open position permitting the supply of fluid through said passage and a closed position shutting off the supply of fluid through said passage, an armature, an electromagnet cooperable

with said armature, said electromagnet being effective when energized to hold said armature in attracted position and said valve element in open position but ineffective to move said armature to attracted position and said valve element to open position, a reset stem movable inwardly for resetting said armature to attracted position and said valve element to open position, a second valve element slidably mounted on said reset stem and arranged to cooperate with the other valve seat to shut off flow of fluid through the passage during a resetting operation, a reset spring abutment member on said reset stem, a reset member fixed on said stem providing

an abutment for said abutment member, a coiled reset spring interposed between said abutment member and an abutment on the valve body for returning the reset stem to its outer position upon completion of the resetting operation, retainer means on said reset stem, and a third valve member fixed on said reset member and cooperable with the valve body to prevent leakage from the valve body along the reset stem in the outer position of said stem, said second spring being arranged within the convolutions of said first spring with its length confined within the length of said first spring.

CLARENCE WANTZ.
